HANDBAG

Irving Pichel, New York, N. Y.

Application April 11, 1952, Serial No. 19,286

Term of patent 3½ years

(Cl. D87—3)

To all whom it may concern:

Be it known that I, Irving Pichel, a citizen of the United States of America, residing in New York, county of New York, and State of New York, have invented a new, original, and ornamental Design for a Handbag, of which the following is a specification, reference being had to the accompanying drawing, forming part thereof.

Fig. 1 is a front perspective view of a handbag, showing my new design.

Fig. 2 is a rear perspective thereof.

Fig. 3 is a front perspective of the handbag as shown in Fig. 1 in open position.

I claim:

The ornamental design for a handbag, substantially as shown.

IRVING PICHEL.
